United States Patent Office.

SAMUEL W. BARR AND EDWIN McGUIRE, OF BELOIT, WISCONSIN.

Letters Patent No. 72,962, dated January 7, 1868.

IMPROVEMENT IN WELLS.

The Schedule referred to in these Letters Patent and making part of the same.

TO ALL WHOM IT MAY CONCERN:

Be it remembered that we, SAMUEL W. BARR and EDWIN McGUIRE, of the city of Beloit, Rock county, in the State of Wisconsin, have invented a certain new and useful Improvement in Iron Wells; and we do hereby declare that the following is a full and exact description thereof, reference being had to the accompanying drawings, and to the letters of reference marked thereon, and making a part of this specification.

Similar letters of reference indicate like parts.

The nature of our invention consists in providing a cylinder-point or short section of tubular iron-well pipe, which may be driven with facility into any soil, clay, hard-pan, or gravel, arranged in such a manner that, in the act of driving, the wire-cloth filter is perfectly protected from injury by contact with gravel or rock, entirely excluding all sand from the chamber, and yet admitting a uniform full flow of water to the pump, without turning or raising the cylinder or tubing. The said improved point for iron wells is secured to the tubing in the usual manner.

Figure 1 is a perspective view of the short section or driving-point of the well-tube complete.

Figure 2 is a sectional view of the bulb-like head of the aforesaid driving-point detached, also showing an edge view of the drill-point B.

Figure 3 is a perspective view of the perforated metallic cylinder or shield, perfectly securing the wire-cloth filter from harm by hard substances in the earth through which the point may be driven.

Figure 4 is a perspective view of the perforated metallic inner cylinder, around which the wire-cloth filter is spread, and to which it is secured by being soldered thereto, the said metallic cylinder infallibly guarding the wire-cloth filter from bulging inwardly from external penetration or pressure, and from being loosened and torn off by suction and carried up through the pump-valve, thus rendering the pump worthless by reason of discharging sand with the water, very soon wearing out the valves and pump.

A, fig. 1, represents the slots or perforations in the chamber of the driving-point, and α the upward-bevelled elongations thereof, so that when the point is being driven, the perforations do not fill with earth, the bevel wedging back the soil and leaving the hole free, instead of driving the earth before it; as a square shoulder would, the bevels also forming a natural channel for the water to flow into the holes downward, the lower shoulders forming a sort of dam, causing the impeding loam to be dissolved and drawn up by and through the pump, freeing the external surface of the chamber from earthy contact, and allowing an abundant supply of water about the point.

The use of the drill-point B effectually prevents the point from sticking fast when being driven through stiff clay or hard-pan, said point forming a sort of auger, by the use of which the well may be sunk in soft or free soil by turning the tubing like an auger, and no driving be required.

We claim the combination and arrangement of the well-tube, soldered filter, and drill-point, all substantially as and for the purpose set forth.

SAMUEL W. BARR,
EDWIN McGUIRE.
